His Attorney.

UNITED STATES PATENT OFFICE.

JOHN A. SUNDQUIST, OF GEORGETOWN, CONNECTICUT.

TOY WAGON.

1,104,574.

Specification of Letters Patent.

Patented July 21, 1914.

Application filed December 12, 1913. Serial No. 806,227.

To all whom it may concern:

Be it known that I, JOHN A. SUNDQUIST, a former subject of the Czar of Russia, who have declared my intention of becoming a 5 citizen of the United States, and a resident of Georgetown, county of Fairfield, and State of Connecticut, have invented certain new and useful Improvements in Toy Wagons, of which the following is a specification.

10 My invention relates to improvements in toy wagons and has for its object the production of a toy wagon which will be ornate in appearance, and which will be adapted to afford considerable amusement by reason of 15 the peculiar arrangement and mounting of figures adapted for rotary and vertical movement when the wagon is drawn along the ground.

20 A further object is the production of a device as mentioned which will be of simple and durable construction and not adapted to readily becoming inoperative.

Other objects will appear hereinafter.

25 The invention consists in the combinations and arrangements of parts hereinafter described and claimed.

The invention will be best understood by 30 reference to the accompanying drawing forming a part of this specification, and in which,

35 Figure 1 is a top plan view of a toy wagon embodying my invention, Fig. 2 is a side elevation thereof, Fig. 3 is a front elevation of the wagon, and Fig. 4 is an enlarged detail section taken on line $\alpha-\alpha$ of Fig. 1.

The preferred form of construction as 40 illustrated in the drawing comprises a platform 1 which is mounted upon wheels 2, said wheels being secured to the respective ends of axles 3 which are mounted in suitable bearings provided at the sides of said platform. Arising from the upper side of 45 said platform are bearing brackets 4 in which are rotatably mounted transversely extending shafts 5 and 6, said shafts being arranged directly over the axles 3, as illustrated. Provided at the ends of the shafts 5 and 6 are pinions 7 which mesh with 50 gears 7' secured to the inner sides of wheels 2, the arrangement being such that, when the wagon is drawn along the floor or ground, said shafts will be rotated.

Rigidly secured in and arising from the 55 platform 1 are posts 8 upon which are mounted for free vertical and rotary move-

ment figures 9 and 9', said figures being of any desired ornate and amusing appearance, but preferably in the form of bears. The figure 9 which is arranged at the rearward 60 end of the platform supports a horizontally disposed bar 10 in its forepaws at the ends of which are supported smaller figures 11 also preferably in the form of miniature bears.

65 Each of the figures 9 and 9' is secured at its lower end to a bevel gear 12, the gears 12 meshing with bevel gears 13 fixed to the shafts 5 and 6, the arrangement being such that when said shafts are rotated the figures 70 9 and 9' will be simultaneously rotated. The gears 13 are eccentrically arranged upon the shafts 5 and 6 so that in the rotation thereof, as just mentioned, the gears 12 and hence the figures secured thereto will be 75 moved vertically at the same time as the same are rotated. At the upper ends of the posts 8 are provided pennants or flags 14 which constitute stops to prevent displacement of the figures 9 and 9' in the event of 80 the wagon being over-turned.

85 Provided centrally in the shaft 6 is a crank 15 upon which is loosely mounted the forward end of a figure 16 also preferably in the form of a miniature bear. The rearward end of the figure 16 rests loosely upon the upper side of the platform, the arrangement being such that, upon rotation of the shaft 6, the figure 16 will be actuated in a manner to imitate a trotting or galloping 90 bear.

95 The entire arrangement is neat and pleasing and will afford considerable amusement for children. The arrangement is simple and economical in construction and hence may be manufactured at a low cost.

100 While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope 105 of the appended claims.

Having described my invention what I claim as new and desire to secure by Letters Patent is:

110 1. A toy wagon comprising a platform; wheels supporting said platform; a shaft rotatably mounted in bearings provided on

said platform; an operative connection between said wheels and said shaft; a post arising from said platform; a figure mounted on said post for free vertical and rotary movement; a bevel gear on said shaft; and a bevel gear having a vertical axis connected with said figure and meshing with and resting upon said first mentioned gear, said gears being held in mesh by gravity, said 10 first mentioned gear being eccentrically mounted upon said shaft, substantially as described.

2. A toy wagon comprising a platform; wheels supporting said platform; gears fixed 15 to said wheels; a shaft rotatably mounted in bearings arising from said platform; pinions on said shaft meshing with said gears; a post arising from said platform; a figure mounted on said post for free vertical 20 and rotary movement; a bevel gear having a vertical axis, said bevel gear being secured centrally to the lower end of said figure; and a bevel gear fixed to said shaft meshing with and resting upon said first mentioned 25 gear, said gears being held in mesh by gravity, said second mentioned gear being eccentrically mounted upon said shaft, substantially as described.

3. A toy wagon comprising a platform; 30 wheels supporting said platform; a rotatably mounted shaft arranged above said plat-

form; an operative connection between said wheels and said shaft; a crank formed in 35 said shaft; and a figure having one end loosely mounted upon said crank and having its opposite end loosely resting upon said platform, whereby, when said shaft is rotated, said figure will be moved back and forth on said platform, substantially as described.

4. A toy wagon comprising a platform; wheels supporting said platform; a shaft rotatably mounted in bearings provided on 40 said platform; an operative connection between said wheels and said shaft; a post 45 arising from said platform; a figure rotatably mounted on said post; a gear connection between said shaft and said figure whereby, when said shaft is rotated, said figure will be simultaneously rotated; a crank formed in said shaft; and a figure having one end loosely mounted upon said crank and having its opposite end loosely resting upon said platform, substantially as 50 described.

In testimony whereof I have signed my name to this specification in the presence of two subscribing witnesses.

JOHN A. SUNDQUIST
